COMBINATION SPORT AND CONVENTIONAL SHIRT

Vali E. Raddatz, Woodhaven, N. Y., assignor to Robert Reis & Co., New York, N. Y., a corporation of New York

Application May 1, 1940, Serial No. 332,797

3 Claims. (Cl. 2—122)

The invention relates to a garment suitable for wear by men and women, either as a sport or open-neck shirt, or as a shirt with conventional type of collar for use with a necktie or the like.

5 It is the general object of the invention to provide a convertible shirt of the character indicated which in either of its forms is properly cut and tailored for such form and which can be conveniently converted from one form into the other, 10 and particularly without the aid of the usual buttons and buttonholes and the like. It is a further object of the invention to provide a convertible shirt, as described, which is simple and inexpensive in construction, neat in appearance, 15 and so cut and the parts so constituted, that a well-fitting garment is obtained, which is free from curling at the collar, the collar being of pleasing form and satisfactory fit both in its open sport and in its closed conventional condition.

20 More specifically, it is an object of the invention to provide a convertible garment of the type indicated, whose front portion, in its preferred form, is composed essentially of two continuous pieces of fabric, one piece extending from a shoulder seam, along the adjacent sleeve seam, to the adjacent side seam of the garment, and across to the other side of the garment where it meets the seams joining the other piece to its adjacent sleeve, each piece extending to the region of the underarm of the opposite sleeve, advantageously to a point on the seam of such sleeve above the adjacent side seam of the garment; at least one of the pieces reaching to the bottom of the garment, and the pieces overlapping in the central chest region, preferably at portions having diagonal edges, such diagonal edges either running to the abovementioned sleeve seams, or cut at a sharper angle, terminating approximately 25 in the region of the inner upper corner of the usual breast pocket, from which point the edge of the fabric piece runs substantially horizontally to the sleeve seam.

25 A further object of the invention is to provide a combination garment constituting a shirt convertible into either the sport or conventional type in which the fabric of the sections which extend across and over at the upper chest region of the garment are folded over in the sport shirt condition of the garment and join gracefully with the front edge of the collar; and the edges of such overlapping and folded over portions run diagonally, as explained above, and are cut on the bias, while inside facings provided on such 30 portions along the two edges are cut on the

straight weave of the cloth, if the cloth is of the woven type, and parallel to the wales of the cloth, if it is of knitted construction, whereby curling and stretching of the diagonal edges are obviated.

35 A still further object of the invention is to provide a novel construction of collar, constituted of two pieces of cloth, one on the top or outer side and one on the bottom or underside, instead of one on the topside and two on the underside, as has been the conventional construction in this 10 general type of garment.

The objects of the invention as briefly set forth hereinabove are attained by imparting certain novel shapes and forms to the sections or panels which are to constitute the front portion of the 15 garment extending from the shoulders to to the bottom of the garment and so combining these sections of fabric as to yield a construction exhibiting the advantages hereinafter to be described in greater detail. Means are also provided for conveniently and easily converting the collar of the garment from the sports type to one of the conventional type, whereby, in conjunction with the novel formation of the component parts of the garment, all buttons and buttonholes and closings of any kind are eliminated.

40 A preferred embodiment of my invention is illustrated by way of example, but not by way of limitation, in the accompanying drawings, in which

Fig. 1 is a front view of a garment in the construction of which my invention has been embodied, with a portion of the front of the garment being shown broken away to illustrate the structure more clearly;

45 Fig. 2 is a front view of the upper portion of the garment, showing the manner of its conversion into a conventional type of shirt with a conventional collar;

50 Fig. 3 is a view of the garment with the collar portion thereof in extended condition showing the manner of securing together the upper portions of the shirt to produce the conventional type of collar illustrated in Fig. 2;

Fig. 4 is a section on the line 4—4 of Fig. 1;

55 Fig. 5 is a section along the line 5—5 of Fig. 3 on an enlarged scale, the section being taken transversely through the collar and the immediately adjacent portions of the shirt;

Fig. 6 is a plan of the pattern constituting the 50 continuous piece of fabric forming the outside panel of the shirt front;

Fig. 7 is a similar view of the second piece of fabric forming the underlying panel of the shirt front; and

Figs. 8 and 9 are the strips of cloth from which the outer and inner sections, respectively, of the collar are formed.

Referring more particularly to the drawings, in which similar reference characters identify similar parts in the several views, 10 is a sheet of fabric constituting the back of the garment and extending from the shoulder line to the lowermost edge of the garment. Substantially the entire exposed front of the garment is formed by a single continuous piece of fabric 11, shown in pattern form in Fig. 6, extending as the garment is viewed in Fig. 1, from the right shoulder seam 12 along the seam 13 of the adjacent right sleeve 14, to the adjacent side seam 15 of the garment, and across to the other side of the garment where it meets the underarm seam 16 of the left sleeve 17 and the seam 18 of the garment, the piece of fabric 11 extending to the bottom edge 19 of the garment. The upper portion of the panel 11 positioned substantially in the central chest region, has a diagonal edge 20 cut at a sharp angle, as shown in Fig. 6, terminating approximately in the region of the inner upper corner 21 of the usual breast pocket 22 and at a point substantially short of the center of the front, from which point the edge of the fabric piece of panel runs substantially horizontally to the sleeve seam 16.

The underlying panel of the shirt front is formed of a separate continuous piece of fabric 23 extending, as viewed in Fig. 1 from the left shoulder seam 24 along seam 25 of the sleeve 17, to the right side of the garment to the underarm seam 26 of the right sleeve 14 and then downwardly through a portion of the extent of the overlying front panel 11. The panel 23 has a diagonal edge 27 terminating at a point 28 substantially short of the center of the front and then extending horizontally toward the underarm seam 26.

Separate strips 28 and 29, constituting facings, are stitched to the panels 11 and 23 approximately adjacent to the neck opening formed by the collar generally designated as 30.

The collar 30 is constituted of two separate strips of fabric 31 and 32, both cut on the straight from the material of which it is constituted, as indicated in Figs. 8 and 9, the two strips being joined at the top of the collar by stitching 33 and at the bottom of the collar to the facings 28 and 29 by stitching 34. The collar, thus constituted, when brought down on the neck opening, will roll naturally when the shirt is open at the neck.

An elongated strip or strap of fabric 35 is secured at one end by means of a snap fastener element 36 to a corresponding snap fastener element on the underside strip 32 of the collar, the strap being adapted to be secured to a snap fastener 37 on the opposite side of the neck opening, to connect the two collar tabs, or to be pivoted about the snap fastener structure 36 to a position shown in dotted lines in Fig. 3, in which position the snap fastener at its outer end may be brought into cooperative engagement with a mating snap fastener element 38 secured upon the collar at a point removed from the fastener 36 by substantially the length of the strap, and thus fasten the strap in a position below the folded-over collar. The strip or strap is hidden beneath the collar when the shirt presents the V-shaped neck opening shown in Fig. 1 but bridges and is fastened to the ends of the col-

lar when the latter is in closed position shown in Fig. 2.

Returning now to the construction of the body of the garment, the edges 20 and 21 of the panels 11 and 23 as hereinbefore set forth, are cut on the bias, while the two inside facing strips 28 and 29 are cut on the straight. This construction eliminates the curling of the edges 20 and 21 and the possibility of stretching of such edges, which would occur if both the edges 20 and 21 and the facing strips were all cut from the fabric on the bias.

The edge of the panel 11, extending from the lower extremity of the edge 20 to the underarm seam 16 is preferably tacked at a point near the lower extremity of the edge 20, and also at a point about one inch from the underarm seam 16. The portion of this edging of the panel 11 which is not tacked may then constitute the opening of the pocket 22, provided so as to extend along the interior face of the panel 11. A similar pocket may be provided on the opposite side of the shirt front with an opening coextensive with the horizontal edge of the panel 23 extending from the lower extremity of the edge 27 to the underarm seam 26. The overlapped portions of the fabric sections between the points 21 and 28 are free and unattached relative to each other.

Obviously, while I have illustrated my novel construction of garment as provided with short sleeves, my invention may be embodied in a garment having long sleeves. Likewise, while I have illustrated an embodiment of my invention in which the rear panel 23 extends to approximately the waistline, such panel may extend to any length along the body of the garment, even to the lowermost edge of the front panel 11.

My invention is equally applicable to all types of woven and knitted cloth or fabric and to any combination of materials and colors.

Having now described the construction of a specific embodiment of my invention, the manner of use thereof, particularly the conversion of the garment from one of the sports type with an open collar, such as illustrated in Fig. 1, to the form thereof illustrated in Fig. 2, will now be described.

If the wearer of my novel garment is desirous of converting the sports type shirt, for instance, after partaking in a game of golf or similar recreational activity, in which he or she desired a freedom of the neckline or shoulder muscles for the strenuous activities involved in the sport, and he or she desires to present a more formal appearance, the wearer can turn the collar 30 upwardly as illustrated in Fig. 3, detach the pointed end of the strap 35 from the fastener element 38, rotate such strap on the fastener 36 to the position of such strap illustrated in full lines in Fig. 3, and secure the free end of the strap to the fastener 37. Upon turning down of the collar 30, the condition thereof illustrated in Fig. 2 will be secured, and a conventional necktie may be worn with the shirt, in the usual manner, with the knot thereof overlying the exposed portion of the strap 35.

It will be noted that no visible fastening structures of any kind, whether buttons, or buttonholes are utilized, either upon the shirt body, with the exception, possibly, of the sleeve cuffs, upon the collar, or upon the fabric constituting such collar.

The garment may be readily donned or taken off by opening the collar to the position thereof

illustrated in Fig. 1, which operation will provide a sufficiently large opening for the passage of the head through such opening. This expansion or dilation of the neck opening is made possible by the relative displacement of the edges 28 and 27 of the two panel sections 11 and 23. The construction of the shirt, however, by reason of the pattern into which the two continuous pieces of fabric constituting the front portions of the shirt have been cut, and their overlapping slightly diagonally over the chest of the wearer, produces a proper setting of the garment upon the body and suspension thereof from the shoulders of the wearer. At the same time, however, there is sufficient resiliency and play between the top sections of the two front panels to provide for sufficient freedom of movement of the body of the wearer without constriction, for instance, as necessitated by indulgence in some active sport. In other words, the novel cut and tailoring of the garment gives the fabric thereof a sufficient degree of extensibility and displacement to have the panels of the garment accommodate themselves to the bodily conditions necessitated by any movement of the body of the wearer.

From what has been said above it will be seen that I have provided a combination sport and conventional outer shirt which includes a front formed with two fabric sections each having an upper edge extending horizontally or substantially horizontally from about the armpit to a point substantially short of the center of the front and thence upwardly in a diagonal direction to the approximate center at the neckline and partially around the neckline. A collar is attached at the neckline and the ends of the collar extend to the diagonally disposed edges to present a closed front shirt when the shirt is brought together or secured at the neck, but when the shirt is separated at the neck to any substantial degree or unsecured forming a V-shaped neck opening defined by folds extending from or substantially from the points of intersection of the horizontal and diagonally disposed edge portions to points on the shoulders. The overlapped parts of the sections, as previously stated, are free and unattached relative to each other between the diagonal edges 28 and 27. This provides for the proper neck opening when putting on or taking off the shirt.

While I have described a specific embodiment of my invention, it is obvious that various changes therein, particularly in the arrangement and configuration of the component parts of the garment, may be made without departing from my invention.

I claim:

1. A combination sport and conventional outer shirt of the pull-over type having a front includ-

ing two fabric sections each having an upper edge extending substantially horizontally from about the armpit to a point substantially short of the center of the front and thence upwardly in a diagonal direction to the approximate center at the neckline and partially around the neckline, and a collar attached at the neckline, the ends of the collar extending to the diagonally disposed edges to present a closed front shirt when the shirt is brought together at the neck, but when the shirt is separated at the neck to any substantial degree forming a V-shaped neck opening defined by folds extending from substantially the points of intersection of the horizontal and diagonally disposed edge portions to points on the shoulders opposite such points of intersections with respect to the center line of the shirt.

2. A combination sport and conventional outer shirt of the pull-over type having a front including two fabric sections each having an upper edge extending substantially horizontally from about the armpit to a point substantially short of the center of the front and thence upwardly in a diagonal direction to the approximate center at the neckline and partially around the neckline, a collar attached at the neckline, the ends of the collar extending to the diagonally disposed edges to present a closed front shirt when the shirt is brought together at the neck, but when the shirt is separated at the neck to any substantial degree forming a V-shaped neck opening defined by folds extending from substantially the points of intersection of the horizontal and diagonally disposed edge portions to points on the shoulders opposite such points of intersections with respect to the center line of the shirt, and a member hidden beneath the collar when the shirt presents the V-shaped neck opening, adapted to bridge and fasten the ends of the collar when the latter is in closed position.

3. A combination sport and conventional outer shirt of the pull-over type having a front including two fabric sections, each having a diagonal edge extending from a point substantially short of the center of the front to the approximate center of the neckline, the portions of the sections between the diagonal edges being overlapped and free and unattached relative to each other, and a collar attached at the neckline, the ends of the collar extending to the diagonally disposed edges to present a closed front shirt when secured at the neck, but when unsecured forming a V-shaped neck opening defined by folds extending from the said points of the diagonal edges substantially short of the center of the front to points on opposite shoulders.

VAL. E. RADDATZ.
